Primary Examiner — Martie K Holtje(74) *Attorney, Agent, or Firm* — Millman IP Inc.(57) **CLAIM**

The ornamental design for a toy flying craft, as shown and described.

DESCRIPTION

FIG. 1 is a perspective view from above and to one side of the new design for a toy flying craft;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top view thereof; and,

FIG. 7 is a bottom view thereof.

The structural features depicted by broken lines have been shown for the purpose of illustrating portions of the toy flying craft that form no part of the claimed design.
